UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Original application filed April 13, 1928, Serial No. 269,684. Divided and this application filed February 18, 1929. Serial No. 340,752.

My invention relates to a slicing machine and particularly to a slicing machine having a rotary knife and means for driving it, of the type wherein a work supporting carriage is provided and means for guiding it across the face of the knife. One object of my invention is to furnish a support for the slices which are being cut. The presence of such a support, which holds the slice in the plane of the larger piece from which it is cut, insures a uniform and efficient severance of the slices from the piece, prevents ragged slices, and prevents slices from being partially severed. A clear, complete cut is insured. Another object of my invention is to prevent the slices from falling into the space between the gauge plate and the carriage, and to insure that each slice cut shall pass through the space between gauge plate and knife to the trough or receiving means. Other objects will appear from time to time in the course of the specification and claims.

The present application is a division of my application No. 269,684, filed on April 13, 1928 and upon which issued United States Patent No. 1,707,654 of April 2, 1929.

I illustrate my invention more or less diagrammatically in the accompanying drawings, wherein—

20 Figure 1 is a front elevation;

Figure 2 is
Figure 1; and

Like parts are indicated by like symbols.

35 throughout the specification and drawings.
A indicates any suitable slicing machine base member having the ground engaging supports or studs A¹. B generally indicates

40 supports or studs A¹ - B¹ generally indicates any suitable housing member or body upwardly projecting therefrom having associated therewith a face plate B¹, normally fixed in position and a gauge plate B² which may be moved toward and away from the 45 plane of the knife as for example by rotation

I do not wish to be limited to any particular means for imparting movement to the gauge plate but I have herein shown lugs B⁴ on the rear of the gauge plate, levers or arms

B⁵ pivoted thereto, themselves pivoted as at B⁶, a gear B⁷ associated with one of said levers and a worm B⁸, in mesh therewith and actuated by the knob B³.

C indicates the knife, it being herein shown as recessed in its forward face as at C¹ in order to permit the peripheral portion C² to project outwardly into and slightly beyond the planes of the face plate B¹. It will be understood that the axis of the knife, in the form herein shown, lies in a generally horizontal plane but is tilted slightly from perpendicularity to the face plate B¹ in order to throw one edge of the knife forwardly into the plane of said face plate. 65

D generally indicates a guide track, herein shown as cylindrical, and mounted at its ends upon the supports D¹. Beneath it is a supplemental track D² herein shown as of rectangular cross-section. D³ indicates a carriage 70
slidable along the track D, provided with a downward extension D⁴ formed to surround the track D² and thus to prevent rotation of the carriage D³ about the track D. D⁵ is any suitable material carrying tray positioned 75 upon the carriage D³. Unless the gauge plate

B² is adjusted so far forward as to lie practically in the plane of the cutting edge of the knife C there will be a space between the gauge plate and the carriage plate D⁶. If this space is left open, bits or slices of material may under some circumstances drop therethrough instead of passing through the space between the knife edge C² and the opposed arcuate edge of the gauge plate. In order to render this impossible and to insure that all slices shall pass through such gap I provide a supplemental horizontal ledge or plane surfaced member, to prevent such slices from dropping down between the gauge plate B² and the carrier plate D⁶. 83 90

Referring in detail to the drawings, I employ a narrow member or shelf G which extends across substantially the entire front of the gauge plate and is secured to the face thereof. Adjacent the knife edge the gauge plate is cut away or slotted as at G¹ and positioned to register with the slot is a fixed meat support G² mounted on any suitable bracket or pedestal G³. The upper surface

G⁴ of the support G² may be slightly above the level of the upper surface of the angle G, in order that it may register closely with the level of the carriage D⁶, as shown in Figure 3. It is in general important that the support G² should closely approach the edge and rear of the edge of the knife and I therefore provide adjusting means, for example the screws G¹⁰ and the slots G¹¹, for effecting whatever adjustment is necessary to maintain the support G² properly positioned in relation to the knife and knife edge.

The edge of the meat support is preferably inclined or beveled as at G⁵ in order to prevent any stoppage or interference of the work or slice as it crosses over and upon the support G². The meat support G² is always up against the edge of the carriage and supports the slice and prevents any particle or fringe or portion of the slice from dropping down between the carriage and the knife. The angle G on the gauge plate serves to keep the last slice from falling off the pusher plate.

It will be realized that whereas I have described and shown a practical and operative device nevertheless many changes might be made in size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In employing a meat or work carriage for supporting the carriage for supporting the work as it is carried across the face of the knife, and in employing the gauge plate against which the work is thrust, whether manually or mechanically, it is important to support the slice while the slice is being cut. Were it possible, which it is not, to have the carriage approach so close to the gauge plate that no interval is left between gauge plate and carriage, there would be no necessity of supporting the slice in the front of the gauge plate. However the mere fact that the gauge plate is adjusted toward and away from the path of the carriage insures that there will be a space between gauge plate and carriage. And furthermore, the increase of the opening between the edge of the gauge plate and the cutting edge of the knife, which determines the thickness of the slice, insures that there will always be a space between carriage, gauge plate and knife at that point, in which the carriage gives no support. I therefore provide a shelf or support which operates with the carriage and which is independent, in its supporting function, of the position of the gauge plate.

Referring to the figures, it will be clear that the shelf G will underlie the edge of the carriage at all normal positions of the gauge

plate and that therefore no slice or fragment of meat can drop down through the space between carriage and gauge plate. Equally important is the lateral extension G⁴ of the fixed shelf member G², which is formed to hug the connecting edge of the knife at all positions of the gauge plate. This insures that the slice, in course of severance, will be supported up to the instant of the final separation of the slice from the work. The portion of the support G² which projects to the rear of the knife supports the slice immediately following severance.

The support at these points prevents partially completed slices and little tail ends of meat from sliding down around the corner of the carriage and getting between the front of the carriage and the knife, and insures the delivery, from the knife edge, of a cleanly cut and completely severed slice.

In view of the frequent practice of using vitreous enamel for carriage and gauge plate the addition of the slice supporting shelf is important. The front of the carriage is necessarily rounded or oval shaped owing to the fact that the enamel will not stick on a sharp corner. This rounding of the parts would tend to provide an opportunity for the escape of small bits of meat, partly completed slices and the like were it not for the employment of the shelf or support.

Also, the shelf, positioned as it is across substantially the entire front of the gauge plate prevents the last slice from falling down between the front of the carriage and the gauge plate.

In the use of my device the angle G, which extends across the major width of the gauge plate, terminates at the beginning of the cut away portion or slot G¹. Here the task of supporting the slice is taken up by the fixed support G², which supports the slice up to the cutting instant. It is always up against the edge of the carriage and also closely hugs the edge of the knife and supports the slice until its separation from the work is completed. Thus it prevents any fringe of meat from dragging over and prevents the slice or any part of the slice from penetrating or dropping into the space between carriage and knife.

I claim:

1. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, a work support mounted upon and outwardly projecting from the gauge plate toward the carriage, and underlying said carriage, and an additional work support fixed upon the slicing machine and underlying a portion of the gauge plate, the two said work

supports lying at substantially the same horizontal plane, the last mentioned fixed work support being positioned adjacent the cutting edge of the knife, and between the knife 5 axis and the first mentioned work support, the gauge plate being movable in relation to said last mentioned fixed work support.

2. In a slicing machine having a rotary knife and means for rotating it, a carriage 10 and means for guiding it along a path across the plane of said knife, a gauge plate lying in a plane generally parallel with the path of movement of said carriage, and means for moving it toward and away from said carriage, a work support mounted upon and outwardly projecting from the gauge plate toward the carriage, and underlying said carriage, and an additional work support fixed upon the slicing machine and underlying a 15 portion of the gauge plate, the two said work supports lying at substantially the same horizontal plane, the last mentioned fixed work support being positioned adjacent the cutting edge of the knife, and between the knife 20 axis and the first mentioned work support, the gauge plate being movable in relation to said last mentioned fixed work support, the edge of the fixed work support farthest from the knife, and facing the first mentioned 25 work support, being bevelled.

3. In a slicing machine having a rotary knife and means for rotating it, a carriage and means for guiding it past the cutting edge of said knife, a gauge plate lying in a 30 plane generally parallel with the path of movement of the carriage, and means for moving it toward and away from the carriage, a work supporting member movable with and outwardly projecting from said 35 gauge plate toward said carriage, and lying in the general plane of the upper supporting surface of said carriage, and extending along a substantial proportion of the width of said gauge plate, but terminating at a 40 point spaced laterally away from the cutting edge of the knife, and an additional work support, normally fixed upon the slicing machine, said fixed work support being positioned in the general horizontal plane of 45 the upper supporting surface of the carriage and being adapted to support the work, and the slices cut therefrom, at the actual zone of cutting engagement of the knife with the work, said fixed work support extending 50 closely adjacent the cutting edge of the knife, and being interposed between the cutting edge of the knife and the end of the first mentioned work support closest to the cutting edge of the knife.

60 Signed at Indianapolis, county of Marion, and State of Indiana, this 13th day of February, 1929.

WILLIAM J. CAMPBELL.
